TABLE OR THE LIKE

Richard G. Reineman, Covina, Calif., and George E. Schaefer, Muskegon Heights, Mich., assignors to Brunswick Corporation, a corporation of Delaware

Filed Apr. 11, 1960, Ser. No. 60,123

Term of patent 14 years

(Cl. D33—14)

FIG. 1 is a top plan view of a table or the like, showing our new design;

FIG. 2 is a side elevational view thereof; and

FIG. 3 is an end elevational view thereof, taken at about the line 3—3 of FIG. 1.

The dominant features of our design reside in the portions shown in full lines on the drawing and is further characterized by a tapered leg and brace member associated with a top of the specific configuration disclosed. In FIG. 2, the broken line showing of the wall surface is for illustrative purposes only.

We claim:

The ornamental design for a table or the like, as shown and described.
